SHAKER CAP

John J. Grantonic, Mingo Junction, Ohio, assignor of twenty-five per cent to Frank McLister, Mingo Junction, Ohio

Application April 28, 1936, Serial No. 76,829

3 Claims. (Cl. 65—45)

This invention relates to that classification of kitchen and table accessories classified in the trade and elsewhere as condiment shakers and has structural reference in particular to so-called 5 combination or two-way salt and pepper shakers wherein the salt is separated from the pepper and the discharge thereof controlled by selectively usable valved cap means permitting requisite discharge of the salt or the pepper at will.

As implied by the introductory paragraph, I am aware that the broad proposition of duplex condiment shakers is old in the art to which the invention relates and it is, therefore, my primary aim to provide a new type of valved closing cap 15 possessed of noteworthy refinements and improvements susceptible of bringing about the new and novel results desired.

Moreover, I aim to provide a structure whose features are in keeping with the modern trend of simplicity and economy, whereby to provide an alternately controllable effectively operable structure capable of easy and natural use.

Other features and advantages will become more readily apparent from the following description and drawing.

In the drawing wherein like numerals are employed to designate like parts throughout the same:—

Figure 1 is a view partly in section and partly in elevation showing what may be described as fragmentary vertical sectional view of a condiment shaker embodying a valved closure and discharge unit constructed in accordance with my own inventive idea.

Figure 2 is a view similar to Figure 1, the sections being at approximate right angles to illustrate the oscillatory counter-weight valve operator or unit.

Figure 3 is a top plan view of what may be described as the inner cap.

Figure 4 is an edge elevational view of the outer closing cap.

Figure 5 is a bottom plan view of Figure 4.

Figure 6 is a fragmentary sectional and elevational view of the so-called inner cap illustrating approximately how the valve lifting or opening operation is accomplished.

In the drawing the condiment shaker proper is denoted by the numeral 7 and is of appropriate 50 glass or similar construction and is divided by a central partition 8 into individual compartments 9 and 10 to contain the respective charges of salt and pepper (not shown). The inner cap fits telescopically into the discharge end of the shaker 55 and is provided with keeper notches 12 which

notches engage over the partition as shown in Figures 1 and 2. There is an outstanding annulus or lip 13 which rests on the mouth of the shaker and is held in place by the complementary flange 14 of the clamping ring 15. The ring is 5 preferably threaded to engage existing threads on the shaker 7. The diametrically opposite salt and pepper discharge ports are denoted by the numerals 16 and 17. The depressed cup-like central portion 18 constitutes the mechanism pocket or 10 chamber.

A slideable valve rod is indicated at 19 and is slidably mounted in suitable guides and the terminals or end portions 20 and 21 function as 15 valving nibs and are projectable into the ports 16 and 17 to control these, in an obvious manner. The central portion of the rod is formed with a U-shaped bend 22 which constitutes an actuating element. Normally, this is centralized and the nibs 20 and 21 fit into and close the ports 16 and 20 17 (as shown in Figure 1).

The oscillatory gravity controlled weighted unit is denoted by the numeral 23 and comprises an oscillatory rocker shaft 24 journalled in an appropriate way in the cap and extending at 25 right angles to and intersecting the valve rod 19. The central portion of this shaft is bent as indicated at 25 to interlock with the actuating element 22 and to function as a sort of a tappet or cam. Mounted on this shaft on opposite sides 30 of the coordinated features 22 and 25 are the eccentric control weights 26 of duplicate construction.

The main or outer closing cap is denoted by the numeral 27 and this fits over the inner valved 35 cap. Its rim portion rests upon the flange 14 and is provided with diametrically opposite clearance notches 27^a and outstanding apertured adapter means 28 forming requisite sifting and shaking elements. These screen-like sifters 28 40 register with the valved portions 16 and 17. The outer cap is a slip-on friction-fit type and may, if desired, be dispensed with. That is to say, the principal control means is the inner valved cap and its self-contained mechanism.

It is evident that when the cooperating caps, as a unit, are in place, the valve ports 16 and 17 are normally closed, that is when the shaker 7 is set in an upright position on the table. On the other hand, it is evident that when the salt 50 shaker is inverted to discharge the salt or pepper as the case may be, the counter-weights swing over as shown in Figure 6 bringing into play the cam co-acting elements 22 and 25. This lifts the valve rod 19 up, uncovering the then lower dis- 55

charge opening 16 and allowing the opposite end 21 to project through and beyond the remaining discharge port 17. Consequently, the mere tilting or inverting of the shaker causes the valve actuating and control means to swing automatically into play for effective results. Then when the shaker is righted to perpendicular position both ports are closed and the contents protected against unnecessary entrance of moisture.

10 The gist of the invention is predicated upon a closing cap having diametrically opposite discharge ports effectively usable, and a single control rod 19 with its end portions projectable into and simultaneously closing the ports, and the 15 oscillatory weighted unit and cam coacting elements between the rod and said unit.

It is thought that persons skilled in the art to which the invention relates will be able to obtain a clear understanding of the invention after considering the description in connection with the drawing. Therefore, a more lengthy description is regarded as unnecessary.

Minor changes in shape, size and rearrangement of details coming within the field of invention claimed may be resorted to in actual practice, if desired.

I claim:

1. A closing cap of the class described includ-

ing a rim portion having diametrically opposite discharge ports, a slidable rod having valving nibs projecting into and closing said ports, oscillatory valve control means mounted in said cap, and including a rocker shaft and eccentric weights of a gravity controlled type carried by said shaft.

2. A valve cap for a double acting condiment shaker including a body having a rim provided with diametrically opposite discharge ports, a slidable valve rod having its end portions normally projecting into said ports and slidably therethrough in a projectable and retractible manner, a rocker shaft disposed at right angles to said rod and mounted in said cap, eccentric weights on said shaft, and cam coacting elements between the rod and shaft.

3. In a valving cap for duplex shakers, a cap having means to attach it to the shaker and including a rim provided with a pair of diametrically opposite discharge ports, a slidably mounted valving member carried by said cap having its end portions slidably projectable into said ports, a weighted shaft confined and mounted for oscillation in said cap, and coacting cam elements between intersecting portions of said shaft and valve member in the manner and for the purposes described.

JOHN J. GRANTONIC.
